Application filed January 22, 1883. Term of patent 34 years.

To all whom it may concern:

Be it known that I, ANDREW COCHRAN, of the city of Philadelphia, county of Philadelphia, and State of Pennsylvania, have invented and produced a new and original Design for a Pattern to be wrought in Two or Three Ply Ingrain and other Carpeting, in such colors as may be desired; and I do hereby declare that the photographic print accompanying this specification conveys to any one skilled in the art of carpet-weaving a clear understanding of the same, and is sufficient to enable such person to use my invention.

What I claim as my invention, and desire to secure by Letters Patent, is—

The design for ornamenting ingrain or other carpeting, as shown in the photographic print accompanying this specification.

In testimony whereof I have hereunto signed my name this 12th day of January, A. D. 1883.

ANDREW COCHRAN.
